UNITED STATES PATENT OFFICE.

JAMES H. TUDOR, OF CINCINNATI, OHIO.

DOOR AND WINDOW CATCH.

1,411,819.

Specification of Letters Patent.

Patented Apr. 4, 1922.

Application filed January 11, 1921. Serial No. 436,482.

To all whom it may concern:

Be it known that I, JAMES H. TUDOR, a citizen of the United States, residing at Cincinnati, in the county of Hamilton and State of Ohio, have invented certain new and useful Improvements in Door and Window Catches, of which the following is a specification.

My invention relates to an improvement in door and window catches. The object is to provide a simple means for effectively fastening any hinged or other movable member both against rattling and being opened from the outside.

This invention includes a plate hinged to the edge of the door, window, or other object, and provided with a notched tenon, a keeper secured at the edge of the door-way or window jamb, and having a mortise to receive the tenon on the hinged plate, and a clasp pivoted to the hinged plate and having a flange constructed and adapted to embrace the latter and the keeper, whereby to securely fasten the parts together on the inside of the door, window, or other movable member.

In the accompanying drawings:

Fig. 1 is a view showing a hinged door with my improved door and window catch applied thereto;

Fig. 2 is an end view of the catch, showing the clasp in two positions in full and dotted lines;

Fig. 3 is a front view showing the hinged plate in two different positions, in full and dotted lines;

Fig. 4 is a detached perspective view of the door and window-catch;

Fig. 5 is a view of the keeper.

In the illustrated form of the invention, A, represents a door, and B, is the door-jamb. A keeper 1 is secured horizontally at the edge of the door jamb, and is provided with a slot or mortise 2.

At the edge of the door adjacent thereto, a plate 3 is secured to the door and hinged at its outer edge is a hinged plate 4. This hinged plate is provided with a tenon 5, and this tenon may have a notch 6 at the lower edge. The tenon is preferably struck up from the plate 4, and extends at substantially right-angles thereto and is curved in the arc of a circle described from the hinged point preferably, so that it will clear in en-

tering the mortise 2 in the keeper. A clasp 7 is pivoted by means of a pin 8 to the upper corner of the hinged plate, and this clasp is doubled over so as to form a flange 9, which embraces and holds together by frictional engagement the outer edges of the hinged plate and keeper, and a portion of the flange may enter the notch 6 of the tenon 5 when the clasp is fully closed or in the position of embracing the adjacent outer edges of the hinged plate and keeper.

My improved door or window catch is simple, composed of few parts, and capable of being easily applied to any door, case-ment window, or any hinged member. It is easily operated, either opened or closed from the inside, and it is most effectual as a means of fastening for the member to which it is applied. Obviously more or less slight changes might be made without unneces-sarily detailing these in the specification.

Holes 10 and 11 may be formed in the clasp 7 and hinge-plate 4, respectively, when my improved door and window catch is used on barn-doors, garages, and other outhouses. A padlock as shown in dotted lines may be inserted through these holes and through the mortise or slot 2 in the keeper, in this way providing a perfect lock on the outside of any door.

I claim:

1. A door and window catch including a mortised keeper, a plate hinged to the ob-ject to be fastened, and provided with a tenon adapted to be swung into the mortise of the keeper, and a clasp pivoted to one of these parts and adapted to embrace both when closed, whereby to hold the hinged plate and keeper together, and provided with a flange adapted to engage and hold the tenon in the mortise.

2. A door and window catch including a mortised keeper, a plate pivotally connected to the object to be fastened, and provided with a tenon adapted to be swung into the mortise of the keeper, a clasp pivoted to one of the parts, and so constructed as to embrace the edges of the clasp and keeper, and provided with a flange the latter being adapted to engage the tenon to prevent withdrawal of the tenon from the mortise, and the parts having openings adapted to regis-ter when the clasp is fully closed to embrace the parts and engage the tenon, and means

passing through said openings to hold the clasp against movement.

3. A door and window catch including two plates hinged together, one of which is adapted to be attached to the movable part to be fastened, a mortised keeper, one of said plates having a laterally extending tenon in

position to swing into the mortise of the keeper, and a clasp constructed and adapted to embrace the plate and keeper when the parts are to be fastened.

In testimony whereof I affix my signature.

JAMES H. TUDOR.
